CLAIM

The ornamental design for a tailpipe chair, as shown and described.

DESCRIPTION

FIG. 1 is a side view of the tall tailpipe chair with saddlebags.

FIG. 2 is a rear view of the tall tailpipe chair with saddlebags.

FIG. 3 is a top view of the tall tailpipe chair with saddlebags.

FIG. 4 is a front view of the tall tailpipe chair with saddlebags.

FIG. 5 is a side view of the short tailpipe chair without

saddlebags showing a second embodiment of my new

design.

FIG. 6 is a rear view of the short tailpipe chair without saddlebags.

FIG. 7 is a top view of the short tailpipe chair without saddlebags; and,

FIG. 8 is a front view of the short tailpipe chair without saddlebags.

The right side view of the short tailpipe chair is a mirror image of the left side.

The right side view of the tall tailpipe chair is a mirror image of the left side.
